Patented Sept. 5, 1916.

UNITED STATES PATENT OFFICE.

HARRY WEIDA, OF HIGHLAND PARK, NEW JERSEY, ASSIGNOR TO THE INDIA RUBBER COMPANY, A CORPORATION OF NEW JERSEY.

STORAGE-BATTERY SEPARATOR.

1,197,312.

Specification of Letters Patent. Patented Sept. 5, 1916.

Application filed May 22, 1915. Serial No. 29,730.

To all whom it may concern:

Be it known that I, HARRY WEIDA, a citizen of the United States, residing at Highland Park, in the county of Middlesex, State of New Jersey, have invented certain new and useful Improvements in Storage-Battery Separators, of which the following is a full, clear, and exact description.

This invention relates to separators for secondary batteries, and has for an object to produce such an article in which the tendency to break is greatly minimized and which can be manufactured much more cheaply than has heretofore been considered possible.

The separators for the electrodes of secondary batteries, as commonly constructed, comprise a thin perforated sheet of hard rubber, provided with longitudinal spacing ribs superimposed thereon. The thin sheet is ordinarily first partially vulcanized, then perforated, then cut to size, reinforced by the superposed ribs, which are united by cement, and the whole article as built up, finished by subjecting to a final or second vulcanization. The principal objections to sheets made as above described, lies in the fact that the thin unprotected top and bottom edges break with a very slight flexing.

By this invention I provide a structure wherein the tendency to break at the edge is very much reduced, all more fully set forth in the following description and illustrated in the accompanying drawings, in which:

Figure 1 is a plan view of a separator made according to my invention; Fig. 2 is a cross-sectional view of the same, taken on the line 2—2, Fig. 1; and Fig. 3 is an enlarged fragmentary sectional view taken on the line 3—3, Fig. 1, showing the edge reinforcement of the same.

In the drawings, 4 designates a thin hard rubber sheet having its long edges provided with parallel ribs 5 integrally and symmetrically formed on both sides of the sheet. Between the ribs 5 and longitudinal of the sheet are additional ribs 6 of smaller dimension formed on one or both sides of the sheet 4, and preferably uniformly separated.

The structure thus far described provides means for maintaining proper separation without obstructing circulation in the battery or causing localized accumulation of sediment tending to short-circuit the plates. To obviate longitudinal breaks from longitudinal flexing, I form at the short edges of the sheet 4 thickened portions 7, clearly shown in Fig. 3. These thickened portions 60 are integrally formed in the mold when the sheet is shaped and are made of less thickness than the longitudinal ribs 5 and 6. This lesser thickness is essential in order that there be no obstacle to the circulation 65 or tendency to cause accumulation of sediment in the battery jar. The thickened edges are preferably made tapering, as shown, in order that no ledges or corners be formed which would tend to catch and 70 retain sediment. This arrangement allows the sediment to reach the "mud space" in the bottom of the jar, thus eliminating the possibility of a short-circuit between the negative and positive plates. The sheet as 75 formed is finished by punching the perforations 8 in the thin portion of the sheet, the thickened edges 7 being left unperforated.

By the above described construction, I provide a separator which will withstand 80 the flexing to which such articles are ordinarily subjected, without, however, interfering with circulation of the electrolyte or the flow of current from one plate to the other in the battery jar. Inasmuch as the 85 sheet and its reinforcements are integral, it can be formed by molding in a single operation.

What I claim and desire to protect by Letters Patent is:

A separator for battery plates comprising a perforated sheet of non-conductive material, longitudinal spacing ribs on opposite sides thereof, and unperforated thickened margins diverging from said sheet to 95 reinforce the same without obstruction to the spaces at each side of the sheet.

Signed at New Brunswick in the county of Middlesex, State of New Jersey, this 18th day of May, 1915.

HARRY WEIDA.
